UNITED STATES PATENT OFFICE.

JAMES L. SCROGGINS, OF BENNINGTON, OKLAHOMA.

STREET-CAR ANNUNCIATOR.

1,350,038.

Specification of Letters Patent. Patented Aug. 17, 1920.

Application filed September 16, 1919. Serial No. 324,146.

To all whom it may concern:

Be it known that I, JAMES L. SCROGGINS, a citizen of the United States, residing at Bennington, in the county of Bryan and 5 State of Oklahoma, have invented certain new and useful Improvements in Street-Car Annunciators, of which the following is a specification.

The present invention relates to improvements in street indicators or annunciators for street cars and is devised to automatically indicate the consecutive stops as the car proceeds.

A primary object of these improvements is 15 to provide a mechanism of this character which possesses simplicity, so as to eliminate so far as possible the likelihood of the mechanism becoming disordered, said mechanism being electrically operated to impart 20 the required increment of movement to a curtain or web bearing street or stop indicia, the operation of the web in one direction storing up energy which subsequently becomes operative when a reversal of the web 25 takes place.

A further object in view is to provide novel means to impart step by step movement to the web and to produce an audible signal to direct attention to the change being 30 made.

A still further object in view is to provide a novel form of circuit closer which is operated from the overhead current wire.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a perspective view of the indicator apparatus forming the subject matter of this invention.

Fig. 2 is a longitudinal sectional view 45 through the indicator casing.

Fig. 3 is a transverse sectional view thereof.

Fig. 4 is a perspective fragmentary view 50 of the web actuating means.

Fig. 5 is a sectional view of the circuit closer used with this apparatus, and

Fig. 6 is a detailed perspective view of the 55 reversing lever and the actuating pawls for actuating the indicator web.

Throughout the following detail description and on the several figures of the draw-

ings, similar parts are referred to by like reference characters.

Referring to the drawings, 1 designates the indicator casing having the window 2 at the front thereof through which the name 60 of the street or stop carried by the web 3 within the casing is displayed, this casing being adapted for arrangement within the car at a convenient place for observation by 65 the passengers.

The web 3 is carried by the upper roller or spool 4 and the lower spool 5 which are journaled within the casing, the said web being rolled from the upper to the lower by 70 the actuating mechanism hereinafter to be described. With reference to the upper roller it will be observed that the shaft 6 therefor carries adjacent one end the pinion 7 which meshes with the gear 8 of the 75 spring motor or drum 9. The tension of the spring of this motor is of a sufficient character to permit the web to be completely rolled from the upper to the lower roller and at such time to actuate the web in the 80 opposite direction as will later be described.

The lower roller is mounted upon the shaft 10 which carries adjacent one end of the spool the notched disk 11 with which a spring 12 coacts to hold the spool in proper 85 position and prevent the web from becoming loosened. The shaft 10 also carries the pinion 13 which meshes with the large gear 14, said gear being preferably disposed between the ratchet wheels 15, 16. These 90 ratchet wheels are adapted to be actuated by the respective pawls 17, 18, which, as will be observed in Fig. 6, are suspended from the extension 19 of the armature 20. The pawls are bent at their extremities so 95 that one will lie upon one side of the gear 14 while the other is arranged upon the opposite side so as to coat with its proper ratchet wheel, the gear 14 acting to hold these pawls in this position. The pawls are connected 100 midway by the cross bar 21 at the end of the reversing lever 22 the pintle connections between this lever and the pawls being such as to permit of vertical movement of the pawls owing to the provision of the slots 23. 105

It will be noticed that the extremity of the extension 19 constitutes a bell tapper coacting with the bell 24 so that each time the extension is actuated the bell will be rung for the purpose of directing attention 110 to the change which is being made. The armature 20 is operated by the conventional

electro-magnet 25 to which the circuit wires 26 are connected. These wires extend from the annunciator casing 1 to the trolley pole 27 of the car, at the upper portion of which 5 they terminate within a housing 28. One of the wires is connected to the stationary contact 29 while the other is connected to the movable contact 30. The latter is adapted to be actuated to open and close the 10 circuit by means of the lever 31 pivoted intermediate its length at 32. The extremity of this lever is in the form of an arcuate plate 33 and is designed to impinge the arm 34 which is supported upon the current wire 15 35 so that said arm or lever 31 will cause opening and closing of the indicator circuit at the proper places for the change of the web to indicate the next stop.

Briefly summarizing the operation of the 20 device, as just indicated, when the car reaches a predetermined point where the circuit closing arm 34 is disposed, the circuit closing means is actuated so as to close the electric circuit to the electro-magnet or magnets 25. This causes downward movements 25 of the armature and extension 19, which in turn depresses the pawl 17 or 18 and actuates the ratchet wheel which is in coöperation with the active pawl. In the position 30 of these pawls shown in Fig. 3 this movement will tend to impart movement to the lower web roller which will wind the web upon the latter and this will bring the name of the next stop imprinted upon its surface 35 opposite the window 2. During movement of the car in the same direction this intermittent movement of the web takes place until the end of the car line is reached. When operating in the opposite direction, 40 the conductor merely shifts the reversing lever 22 in the proper direction to bring the pawl 18 into coöperative relation with its ratchet wheel. The movement of the ratchet and gears will now be reversed and the web 45 will be rolled upon the upper roller under the action of the spring motor 9. As already mentioned the bell or signal is operated each time the change of street name takes place. As a detail of this mechanism

a switch is usually interposed in the circuit, 50 as designated at 36 so that the operation of the annunciator may be discontinued when so desired. This enables the annunciator to be set at proper positions according to the route followed by the car, a manual wheel 55 37 being provided upon the lower roller for this purpose.

Having thus described my invention, what I claim as new is:

1. A street annunciator of the class described comprising a web, rollers upon which said web is adapted to be wound, and actuating mechanism for effecting the winding operation comprising an electro-magnet, an electric circuit therefor, a circuit closer 60 65 adapted to be intermittently operated, ratchet mechanism including spaced pawls suspended from the armature of the electro-magnet, and a gear member interposed between said pawls to hold them in operative 70 position, said gear being connected to one of the web rollers to actuate the same.

2. A street annunciator comprising casing, spaced web rollers journaled therein, a web adapted to be wound from one roller to 75 the other in either of reverse directions, and means to move the web comprising an armature lever, a solenoid for actuating said lever, a pair of pawls pivotally connected at corresponding ends to the lever, ratchet 80 wheels with which said pawls coöperate and connected with one of the web rollers, a signal comprising a bell, and a tappet carried by said armature lever and arranged to strike the bell as the lever is operated 85 to actuate said pawls.

3. An annunciator substantially as claimed in claim 2 wherein the means connecting the ratchet wheels and one of said rollers consists of a gear operatively connected to the 90 roller and located intermediate the ratchet wheels, and a lever pivotally mounted upon the axis of said gear and having connection with the said pawls to shift the latter to effect engagement of one or the other pawl 95 with its respective ratchet wheel.

In testimony whereof I affix my signature.

JAMES L. SCRÖGGINS.
